Fig. 2.

Fig. 3.

FIG. 1 is a front perspective view of a clock showing my new design;

FIG. 2 is a top plan view thereof; and

FIG. 3 is a partially sectioned side elevational view of the clock taken along line 3—3 of FIG. 2.

The back of the clock is substantially plain.

The dominant features of my design are characterized by the clock face having hour numerals positioned on square, unmarked areas disposed along the square hour numeral track and a band of closely spaced concentric lines within the track following the same square track pattern.

I claim:

The ornamental design for a clock, as shown and described.
